UNITED STATES PATENT OFFICE.

NATHANIEL YOUNG, OF NEWMARKET, NEW HAMPSHIRE.

SPEED-INDICATOR.

No. 800,046.

Specification of Letters Patent.

Patented Sept. 19, 1905.

Application filed January 28, 1905. Serial No. 243,070.

To all whom it may concern:

Be it known that I, NATHANIEL YOUNG, a citizen of the United States, residing at Newmarket, in the county of Rockingham and State 5 of New Hampshire, have invented new and useful Improvements in Speed-Indicators, of which the following is a specification.

This invention relates to speed-indicators designed especially for use upon automobiles, 10 and has for its objects to produce a comparatively simple inexpensive device of this character which may be readily applied, one which will accurately indicate the attained speed of the machine and respond readily to variations 15 in such speed, and one which is wholly free from liability of becoming disordered.

To these ends the invention comprises the novel features of construction and combination of parts more fully hereinafter described.

20 In the accompanying drawings, Figure 1 is a side elevation, partly in section, of a motor-vehicle having my improved indicator applied thereto. Fig. 2 is a top plan view of the indicator. Fig. 3 is a horizontal transverse section taken on the line 3 3 of Fig. 4. Fig. 4 is a vertical transverse section taken on the line 4 4 of Fig. 2. Fig. 5 is a detail perspective view of the hand or pointer and its stem. Fig. 6 is a perspective view of the rotary hub.

25 Referring to the drawings, 1 designates a motor-vehicle having a bottom 2 and a running-gear including axles 3 and transporting-wheels 4, these parts, which are conventionally shown herein, being of the usual or any 30 preferred construction and material.

Attached to one of the wheels 4 for rotation therewith is a friction-gear 5, frictionally engaged with a corresponding pinion 6, supported by a bearing 7 and attached for imparting 40 motion to a flexible operating-shaft 8, having a rigid vertical portion 9 extended through the bottom 2 of the vehicle and journaled for rotation in a suitable bearing 10, depending from the bottom of a casing 11, which incloses 45 the mechanism to be described of the speed-indicator.

Provided upon the top 12 of the casing is a graduated dial 13, over which is arranged for movement a hand or pointer 14, designed 50 to register upon the dial the speed in miles per hour of the vehicle, said pointer being fixed upon a squared stem 15, which fits in a corresponding socket 16, formed centrally and longitudinally through a cylindrical member 55 or barrel 17, arranged for rotation within a fixed sleeve 18, sustained within the casing 11 to

depend centrally from the upper wall 12 thereof, there being provided on the member or sleeve 18, which is non-rotatable, an inwardly-projecting pin or stud 19, designed for engagement with and to travel in a spiral cam groove or way 20, formed in the barrel 17.

Arranged for vertical sliding movement upon and normally inclosing the sleeve 18 is a second sleeve 21, connected by links 22 with 65 governor-weights 23, which are in turn connected by links 24 with the upper end of the shaft 9, the weights and sleeve 21 being through the link connections fixed for rotation with the shaft 9, while upon the sleeve 70 21 there is provided a pair of inwardly-projecting pins or studs 25, designed to travel in a peripheral groove 26, formed in the surface of the barrel 17 at a point adjacent the normally lower end of the latter.

In practice and during travel of the vehicle the shaft 8 will, owing to its operative engagement by means of the friction-gear and pinion with the ground-wheel 4, be driven by the latter and will in turn impart a rotary 80 motion to the shaft 9, the speed of the latter shaft being of course properly timed to accord with the speed of the vehicle. As the shaft 9 rotates it will impart a corresponding movement to the governor-weights 23 and 85 sleeve 21, and of course as this speed increases the weights 23 will, as is common in governors of this type, move outward through centrifugal force, thus drawing the sleeve 21 downward, the barrel 17 being at the same 90 time drawn downward owing to engagement of the pins 25 with the groove 26. Downward movement of the barrel 17 serves, through the action of pin 19 within the spiral groove 20, to impart a movement to the barrel 17 for 95 causing travel of the hand 14 over the face of the dial 13, to thus indicate the attained speed of the vehicle. As the speed decreases the weights will, through the medium of a spring 27, be returned to normal position, thus reversing the movement of the parts and moving the hand backward to normal position. It will be observed in this connection that the 100 governor mechanism will respond readily to variations in the speed of the vehicle and will thus accurately move the hand for indicating such speed, and, furthermore, that as the parts are of simple nature and their number reduced to a minimum liability of the device becoming disordered and rendered imperfect 105 in action is materially reduced, if not wholly obviated.

110

From the foregoing it is apparent that I produce a simple efficient device which will admirably perform its functions to the attainment of the ends in view, it being understood that minor changes in the details herein set forth may be resorted to without departing from the spirit of the invention.

Having thus fully described the invention, what is claimed as new is—

- 10 1. In a speed-indicator, a rotary shaft, a fixed sleeve, a second sleeve slidable thereon, a stud provided on the fixed sleeve, a barrel housed in the latter and connected for movement with the slidable sleeve, said barrel having a spiral groove engaged by the stud for rotating the barrel during longitudinal movement of the same, governor-weights connected with the slidable sleeve and shaft and operable by the latter for moving the sleeve and barrel, a pointer operatively engaged with and movable by the barrel, and a dial over which the pointer moves.
- 15 2. In a speed-indicator, a rotary shaft, a fixed sleeve, a barrel housed and movable longitudinally therein, a stud carried by one of said parts and the other having a spiral groove engaged by said stud for rotating the barrel during longitudinal movement of the latter, a second sleeve slidable upon the first-named
- 20 sleeve and connected with the barrel for mov-
- 25
- 30

ing the same, governor-weights connected with the slidable sleeve and shaft and operable by the latter for moving the sleeve and barrel, a pointer operatively engaged with and movable by the barrel, and a dial over which the pointer moves.

3. In a speed-indicator, a rotary shaft, a fixed sleeve, a second sleeve slidable thereon, a stud provided on the fixed sleeve, a barrel housed in the latter and connected for movement with the slidable sleeve, said barrel having a non-circular axial opening and provided with a spiral groove engaged by the stud for rotating the barrel during longitudinal movement of the same, governor-weights connected with the slidable sleeve and shaft and operable by the latter for moving the sleeve and barrel, a stem of cross-sectional form corresponding to and slidably seated in the axial opening in the barrel, a pointer fixed upon the stem for rotary movement with the barrel, and a dial over which the pointer moves.

In testimony whereof I affix my signature in presence of two witnesses.

NATHANIEL YOUNG.
